UNITED STATES PATENT OFFICE.

JEFFERSON D. PARK, OF SHERMAN, TEXAS, ASSIGNOR OF ONE-HALF TO GEORGE R. DAUGHERTY, OF SHERMAN, TEXAS.

GARMENT HANGER.

Application filed November 7, 1923. Serial No. 673,377.

To all whom it may concern:

Be it known that I, JEFFERSON D. PARK, a citizen of the United States, residing at Sherman, in the county of Grayson and State of Texas, have invented certain new and useful Improvements in Garment Hangers, of which the following is a specification.

This invention relates to a garment hanger, and particularly to a construction embodying a folding hanger arm adapted to be supported by an article of furniture.

In previous constructions of this character it has been necessary to manually adjust the hanger arm for use and to secure it in such position by a clamping device, and such hangers generally required considerable space when in folded position so that they could not be practically used when only a limited space was available adjacent the article of furniture to which they were applied.

This invention has for an object to provide a novel and improved construction in which the hanger arm is automatically raised in its position for use and there held by a latch to sustain the weight of the garments disposed upon the arm. A further object of the invention is to provide a construction in which the arm is provided with a spring controlled drum the tension of which may be adjusted as desired and said drum disposed adjacent a latch member so that it will be automatically latched in either its raised or lowered position.

A further object of the invention is to provide an improved construction of casing for supporting the hanger arm, having means by which it may be adjusted in its relation to the supporting clamp so as to be used in different positions upon the article of furniture to which it is applied.

A still further object of the invention is to present a novel form of support applied to the hanger arm and adapted to receive a coat hanger upon either side of said arm and permit the ready and convenient detachment of said hanger from the support.

Other and further objects and advantages of the invention will be hereinafter set forth

and the novel features thereof defined by the appended claims.

In the drawing:

Figure 1 is a perspective showing the invention applied in different positions upon an article of furniture;

Figure 2 is an enlarged side elevation thereof;

Figure 3 is a top plan;

Figure 4 is a detail section on line 4—4 of Figure 2;

Figure 5 is a section on line 5—5 of Figure 7;

Figure 6 is a similar view on line 6—6 of Figure 7;

Figure 7 is a section on line 7—7 of Figure 3.

Figure 8 is a side elevation of a modified form of clamp; and

Figure 9 is a section on the line 9—9 of Figure 8.

Like numerals refer to like parts throughout the several figures of the drawing.

The invention is adapted for application to any desired support but is particularly designed and herein shown as applied to an article of furniture such as the post 10 of a bed. For the purpose of such application

a clamp member 11 is provided and carries a cooperating clamp 12 secured thereto by fastening means 13, these members being suitably lined with a fabric 14 to prevent scarring or injury to the bed post. The clamp member 12 is provided with pivoting ears 15 which as shown in Figure 7 are preferably spaced from each other to receive a cooperating pivot lug 16 carried by the drum casing 17 for the hanger arm 18. These ears and lugs are connected by a pivot 19. The opposite face of the casing 14 is provided with pivot lugs 20 similar to the lugs 16 which permits the pivotal mounting of the casing upon either face thereof so that it may be changed from the right to the left hand side of a bed, as indicated by full and dotted lines, respectively, in Figure 1.

These lugs 20 are extended from an enclosing casing 21 secured to the casing member 17 by suitable fastening devices, as indicated at 22, and this casing encloses a

drum or cylindrical body 23 from which the hanger arm 18 extends.

This drum is formed upon its periphery with seats or recesses 24 and 25 adapted 5 to cooperate with a latch 26 which is pivoted upon the casing 21 as shown in Figure 6. Any desired form of latch may be used for this purpose but a preferred construction is shown in which the bolt member 27 is 10 slidingly mounted in an aperture 28 extending through the flanges of the casing members and provided with a bearing roller 29 at its inner end which is adapted to ride upon the periphery of the drum and enter 15 either of the seats therein, dependent upon the position of the hanger arm. This bolt is conveniently operated by a pivoted lever 30 and normally projected inward by a spring 31 applied to this lever. This lever 30 is 20 pivoted upon a supporting base 32 from which a fixed finger piece 33 extends to cooperate with the finger piece 34 upon the latter. Pressure upon this finger piece raises 25 the bolt member to permit free movement of the drum and hanger arm.

The drum 23 is normally held under spring tension so that the arm will be in raised position, and the movement of the arm to lowered position tensions such spring. 30 The construction for this purpose comprises a spring 35 disposed in the recess 36 of the drum and secured at one end 37 thereto and at its opposite end to the pivot 38 about which the drum rotates. For the purpose 35 of tensioning the spring 35 to the desired degree for lifting the arm to raised position the shaft of the pivot is provided with an angular end 39 adapted to receive a crank or key and with a ratchet wheel 40 normally held by a pawl 41 under tension of a spring 42 disposed in the casing member 21. In assembling the parts it is desirable to withdraw this pawl so that the ratchet may be disposed in proper relation thereto, 45 and for that purpose a release rod 43 extends outward from the casing and is provided with a handle 44.

The supporting arm 18 may be provided 50 with any desired means for supporting garments or other articles thereon, such as a shoe tree as indicated at 45 and lateral supporting pegs 46. The arm also has secured thereon a support for a coat hanger which comprises the yoke 47 embracing the 55 arm and having the U-shaped portions 48 at each side thereof terminating in retaining sockets 49 for the coat hanger 50. The free end 51 of the plate from which this support is formed may be tensioned outward for the 60 removal of the hanger, as indicated by dotted lines in Figure 4, and under other conditions retains the hanger against accidental displacement. This construction permits 65 the support of clothes hangers at opposite sides of the arm and spaced therefrom, or

the adjustment of such a hanger from one side of the arm to the other, as found desirable in the particular location of the device.

The invention is shown in Figure 1 as applied to a bed frame of a circular construction and in Figures 8 and 9 a form of supporting clamp is shown adapted for attachment to a support of rectangular cross section. Such a support comprises the opposite members 52 provided with a lining 53 and having flanges 54 which abut each other to permit a limited pivotal movement. The plates 52 are held in assembled relation by a cross bolt 55 and are adjusted into 70 clamping relation with the support by means of the screws 56 carried by the turn buckle 57 and bearing against the ends 58 of the plates 52. One of these plates is provided 75 with pivoting eyes 59 to receive and support the drum of the hanger arm as described in connection with Figures 1 to 7.

It will be seen that in the use of this hanger the supporting arm is normally moved into its raised position by the tension of the spring drum, and automatically latched as the recess in this drum passes beneath the bolt for that purpose. The weight of the articles upon the arm is carried by this bolt member so that a firm support is 90 secured and when the arm is desired to be folded or lowered the latch is momentarily released and the arm manually swung downward until the bolt enters the opposite recess by which the arm is held in its lowered 95 position and the spring tensioned by such movement. The construction of the supporting arm provides for the most convenient support of articles of clothing and the arrangement of the coat hanger is such that it 100 may be bodily removed and changed from one member of the support to another as found desirable. The arrangement of the hanger is such that it may be pivoted from either side so as to provide a support for the 105 garments either at the right or left of the bed, or may be used at both sides thereof as 110 indicated in Figure 1.

By providing such a hanger for attachment to a bed convenient means is found for 115 properly supporting the clothing upon retiring and the tendency to hang clothes upon the wall of the room or over tables and other articles avoided.

The invention presents a simple, efficient, 120 and economically constructed clothes hanger in which the supporting arm is automatically raised into position for use by simple pressure upon the retaining latch, and is latched against further depression when 125 reaching such position.

While the details of this invention and the 130 means for its support have been specifically shown and described, still the invention is not confined thereto as changes and altera-

tions may be made without departing from the spirit thereof as recited in the following claims.

Having thus described my invention, what I claim as new and desire to secure by Letters Patent is:

1. In a garment hanger, a pivoted arm, means for retaining the arm suspended beneath its pivot, and means for automatically 10 raising said arm into horizontal supporting position.

2. In a garment hanger, a pivoted arm, means for retaining the arm suspended beneath its pivot, means for automatically 15 raising said arm into horizontal supporting position, and automatic latching means for retaining said arm in such supporting position.

3. In a garment hanger, a pivoted arm, 20 a releasable latch for retaining the arm suspended beneath its pivot, means for automatically raising said arm into horizontal supporting position, and automatic latching means for retaining said arm in 25 such supporting position.

4. In a garment hanger, a casing, a hanger arm provided with a drum pivotally mounted within said casing, a spring connected to 30 said drum to automatically raise said arm into a horizontal supporting position, and a latch member mounted upon the casing and adapted to engage said drum to retain the arm in either raised supporting position or in lowered position suspended beneath its 35 pivot.

5. In a garment hanger, a casing, a drum pivotally mounted therein and provided with a plurality of seats upon its periphery, a hanger arm extended from said drum and positioned beneath its pivot, a spring connected 40 to said drum for normally raising the drum into horizontal supporting position, and a latch device mounted upon the casing and adapted to engage either of the seats upon 45 the drum in the movement of said arm.

6. In a garment hanger, a casing, a drum pivotally mounted therein and provided with seats upon its periphery at its opposite extremes of travel and an intermediate releasing face, 50 a hanger arm extended from said drum, a spring connected to said drum for normally raising the arm into horizontal position for use, a pivoted latch lever mounted upon the

casing, and a bolt carried by said lever and adapted to ride upon said face and engage 55 the seats upon said drum.

7. In a garment hanger, a casing, a drum pivotally mounted therein, a hanger arm extended from said drum, a spring connected to said drum and the pivot shaft thereof to 60 automatically raise the drum into horizontal position, a ratchet member upon said shaft, a cooperating pawl carried by the casing to engage said ratchet whereby the tension of said spring may be adjusted, a tension 65 spring for retaining said pawl in contact with the ratchet, and means extending through the casing for withdrawal of the pawl from said ratchet.

8. In a garment hanger, a casing, a hanger 70 arm pivotally mounted therein for adjustment from a suspended position beneath its pivot to a horizontal supporting position, pivot lugs extended from the opposite faces of said casing, and a supporting member 75 having cooperating lugs for the pivotal mounting of either of the casing lugs to permit reversal of the casing relative to said supporting member.

9. In a garment hanger, a supporting 80 clamp comprising opposite members pivoted upon each other intermediate their ends to form clamping and pressing extensions, an expanding screw device mounted between said pressure extensions and adjustable to 85 separate the same for engaging the clamping extensions upon a support.

10. In a garment hanger, a casing provided with pivoting lugs and a fixed finger piece upon its periphery, a drum disposed 90 within said casing and having a hanger arm extended therefrom, a pivoted latch member mounted upon the casing lugs and adapted to engage said drum, a finger piece upon the latch member cooperating with the finger 95 piece upon the casing, and a spring disposed to separate said finger pieces.

11. In a garment hanger, a supporting arm, and a coat hanger support provided with an open yoke adapted to seat over said arm and extended at opposite sides to form loops adapted to removably embrace a coat hanger 100 at either side of the yoke.

In testimony whereof I affix my signature.

JEFFERSON D. PARK.
